CLAIM

I claim the ornamental design for the ice skate blade, as shown and described.

DESCRIPTION

FIG. 1 is a right side elevational view of an ice skate blade of the present design;

FIG. 2 is a left side elevational view of the ice skate blade of FIG. 1;

FIG. 3 is a rear elevational view of the ice skate blade of FIG. 1;

FIG. 4 is a front elevational view of the ice skate blade of FIG. 1;

FIG. 5 is a top plan view of the ice skate blade of FIG. 1; and,

FIG. 6 is a bottom plan view of the ice skate blade of FIG. 1.

The broken lines shown in FIGS. 1-6 are for illustrative purposes only and forms no part of the claimed design.
